UNITED STATES PATENT OFFICE.

JONATHAN JOHNSON, OF LOWELL, MASSACHUSETTS.

REGULATING-VALVE.

SPECIFICATION forming part of Letters Patent No. 775,823, dated November 22, 1904.

Application filed August 13, 1904. Serial No. 220,669. (No model.)

To all whom it may concern:

Be it known that I, JONATHAN JOHNSON, a citizen of the United States, residing in Lowell, in the county of Middlesex and State of Massachusetts, have invented an Improvement in Regulating-Valves, of which the following description, in connection with the accompanying drawing, is a specification, like letters on the drawing representing like parts.

10 The present invention relates to a pressure-regulating valve, and is designed especially for the control of illuminating-gas, the invention being embodied in a novel construction and arrangement whereby the valve may be 15 adjusted for a certain pressure, being also automatic in its adjustment where the pressure is variable.

10 In accordance with the invention the valve, which is in the nature of a gravity-valve adapted to be opened by the pressure of the gas or other fluid when the supply-outlet is opened, is wholly contained within a casing, the valve resting upon a valve-seat at the inlet and controlling the flow of gas from said inlet to 25 the valve-chamber, which is provided with a suitable outlet leading to the delivery-pipes.

15 The invention is further embodied in a construction whereby the center of gravity of the valve is automatically shifted in accordance with the position of the valve, so that as the pressure behind the valve decreases with relation to the pressure beyond it the tendency of the valve to close by gravity is correspondingly decreased.

20 35 The drawing is a vertical section of a pressure-regulating valve embodying the invention with parts shown in elevation.

40 The pressure-regulating valve is shown as a disk a , contained within a valve-shell A and normally resting upon a valve-seat A^2 within the shell, the said seat controlling the inlet-passage A^3 , through which the gas controlled by the valve enters the shell, which is provided with the outlet-passage A^4 , leading to the system which is to be supplied. The valve is normally held in position by gravity and is weighted sufficiently to remain closed when all the burners in the system to be supplied are shut off, so that there is no preponderating pressure in the inlet portion, the weight, how-

ever, being insufficient to prevent the opening of the valve as soon as any outlet is opened and the pressure beyond the valve thereby reduced.

In order to render the valve self-regulating, 55 it is provided with means for shifting the center of gravity of the weight which holds it closed in accordance with the position of the valve relative to its seat, so as to reduce the closing effect of the weight in accordance with 60 the reduction of the preponderating pressure of the inflowing gas.

In the construction shown the disk a is pivotally supported at a^2 and is provided with an adjustable weighted member a^3 , which tends 65 to hold the valve closed, it being obvious that the closing tendency may be varied by shifting the position of the weighted member a^3 with relation to the valve-disk a , upon which it is supported. For this purpose the said 70 member a^3 is shown as held in a yoke or support a^4 by means of a set-screw a^5 and is adjustable in said yoke when the set-screw a^5 has been released by means of an adjusting-screw a^6 , whereby the said weighted member 75 can be shifted with relation to the valve-disk, thereby changing the position of the center of gravity of the valve. In addition to such initial adjustment, however, the valve is arranged to be automatically adjustable in accordance with the conditions of consumption and supply, so that as the pressure decreases at the outlet end of the shell the valve will 80 open wider, closing automatically to cut down the pressure as the burners are turned off. 85 This is accomplished by providing the valve-disk with means for automatically shifting the center of gravity as the position of the valve varies, such center of gravity being moved toward the pivotal support as the valve 90 opens.

In the construction shown the weighted member a^3 is a tube containing a shiftable weight—such, for example, as a quantity of mercury—which is capable of flowing toward 95 the pivot as the valve lifts, thus shifting the center of gravity and reducing the actual resistance of the weight to the opening of the valve. In order to prevent the valve from opening beyond a certain limit, the valve-sup- 100

port is provided with an adjustable stop a^7 , adapted to be engaged by the end of the weight member a^8 when the valve has been opened to the fullest extent desired. In order that 5 the valve may be readily accessible for purposes of adjustment, &c., the valve-shell A is provided with a removable cap or cover A^5 .

It is to be understood that while the construction herein shown and described constitutes a practical embodiment of the invention such construction may be varied or modified as to the means for providing the initial adjustment, the material used as the shiftable weight, &c., without departing from the invention.

What I claim is—

1. In a pressure-regulating device, the combination with a valve-shell provided with an inlet and an outlet, the said inlet being provided with a valve-seat within the shell; a valve maintained by gravity against said seat; and

means for shifting the center of gravity of said valve in accordance with the position thereof with relation to said seat, as set forth.

2. In a pressure-regulating valve, the combination with a valve-shell having an inlet and an outlet; a disk valve coöperating with a seat at said inlet, said disk valve being pivotally supported with relation to said seat; and a weighted member supported on said valve and adjustable thereon with relation to the pivotal support for said valve; the weight being loosely contained in said weighted member, substantially as described.

In testimony whereof I have signed my name 35 to this specification in the presence of two subscribing witnesses.

JONATHAN JOHNSON.
